M. T. Hitchcock Inventor.

United States Patent Office.

M. T. HITCHCOCK, OF SPRINGFIELD, MASSACHUSETTS.

Design No. 3,617, dated August 17, 1869.

DESIGN FOR A CAR-VENTILATOR DOOR AND FRAME.

The Schedule referred to in these Letters Patent and making part of the same.

To all whom it may concern:

Be it known that I, M. T. HITCHCOCK, of Springfield, in the county of Hampden, and State of Massachusetts, have invented a new and original Design for Car-Ventilator Door and Frame; and I do hereby declare the following, when taken in connection with the accompanying drawings, and the letters of reference marked thereon, to be a full, clear, and exact description of the said design, and which said drawings constitute part of this specification, and represent in—

Figure 1, a front elevation of the frame and doors.

Figure 2 is a vertical section through line U V of fig. 1; and

Figure 3 is a horizontal section through line A B.

My invention relates to the form or shape of the ventilator-frame and door, which is placed within the car, and upon the side of the deck of what is known as a "Monitor-car;" and the following is a description of the same.

In the drawings—

O is the part of the frame which is placed against the surface of the car, and the part D extends forward by a compound curve, as shown more fully in fig. 2.

The upper part has a large rectangular opening

therein, in which are the doors L and L', the form of the door, with its spindle F and handle H, being shown more fully in fig. 3.

The part C, which passes across the frame from side to side, is curved outward, or toward the front, as shown more fully in fig. 2, and the top of the part C, at a', has a ledge extending across the top of said part C; and behind this ledge a' is a recess, a, also extending across, behind the entire length of said ledge a'.

The upper part, N, is also curved outward toward the front, upon about the same line of curvature as the part C.

Fig. 2 and fig. 3 show the appearance of the doors when open, fig. 2 showing the door as partially open, and the dotted lines t showing their position when wide open.

Having thus described my invention—

What I claim, and desire to secure by Letters Patent, is—

The design for car-ventilator door and frame, herein set forth.

M. T. HITCHCOCK.
